UNITED STATES PATENT OFFICE.

JAMES D. SHIPTON, OF VANCOUVER, BRITISH COLUMBIA, CANADA.

ELECTRIC IRON-ORE-SMELTING FURNACE.

1,338,103.

Specification of Letters Patent. Patented Apr. 27, 1920.

Application filed September 22, 1919. Serial No. 325,376.

To all whom it may concern:

Be it known that I, JAMES D. SHIPTON, a citizen of the Dominion of Canada, residing at Vancouver, in the Province of British Columbia, Canada, have invented certain new and useful Improvements in Electric Iron-Ore-Smelting Furnaces, of which the following is a specification.

This invention relates to an electric furnace which has been particularly designed to smelt refractory ferrous ores and provide a means for blending the output from a series of separate smelting chambers in a unified delivery whereby a more uniform grade of metal may be obtained from possibly variable ore charges and with an economical application of current and of the heat generated therefrom.

These objects are obtained by arranging a series of separately operable electric furnaces concentrically around a common mixing chamber into which each furnace chamber may separately deliver its molten metal charge and from which the massed charge may be drawn for casting into pigs or otherwise, as required. The smelting furnace chambers and the common mixing chamber are combined within a unit structure whereby the heat and operating expenses are conserved. The waste heat from the smelting operations is utilized to heat the ore prior to delivery into the furnace chambers and to heat the air by which the furnace gases are diluted.

The invention is particularly described in the following specification, reference being made to the drawings by which it is accompanied, in which:

Figure 1 is an incomplete plan and part horizontal section of the furnace.

Fig. 2 is a vertical section on the line 2—2 in Fig. 1.

Fig. 3 is a vertical cross section of one of the furnace chambers on the line 3—3 in Fig. 2, and

Fig. 4 is a diagram showing the three phase delta connection of the serving current to the carbon electrodes.

The furnace comprises a circular chamber 2 built of fire-brick or the like refractory material, the bottom of which chamber is slightly above the pig casting floor 3 that

the metal may flow thereto through a tap hole 4 to be referred to later. Around this circular chamber 2 is built a ring of separate smelting chambers 5, the bottoms of which are at such height above that of the central chamber 2 that they may be separately tapped into the central or mixing chamber 2.

The walls of these smelting chambers 5 are parallel to their radial middle lines, so that a triangular segmental space 6 is formed between each pair of chambers 5.

The carbon electrodes 7 and 8 are introduced through the arched roof of the furnace in the radial middle line and are electrically connected on the three phase delta system.

Ore is fed to the several chambers 5 through chutes 9 from a central cone hopper 10 which forms an upward extension from the circular mixing chamber 2. At the delivery of the ore chute 9 into the furnace a curtain wall projects downward below the carbon ends which wall is arched at the lower end.

The roof of each furnace has an air space 11 to which a current of cold air is delivered at 12, and after traversing the roof of the furnace, which it prevents becoming excessively heated, the heated air is delivered into an annular chamber or wind box 13 from which twyers 14 deliver it into the several furnace chambers at the approximate level of the ore delivery but on the opposite side. The delivery of this air dilutes the gases generated from the ore and affords a better conducting atmosphere.

The products of combustion are withdrawn through the ore delivery chute 9 to which a connection is made at 15 to the suction of a fan blast or the like.

From the bottom of each furnace chamber a tapping outlet 16 delivers into the outer end of a duct 17 which slopes backward beneath each chamber 5 and delivers into the central mixing chamber 2. The ring of furnaces 5 is carried on an arched gallery 18 across beneath which the molten metal is conducted in a launder to the casting floor 3.

The segmental spaces 6 between the furnace chambers 5 may be charged with black sand, when such is being reduced in the fur-

naces, or with the fine dust of any ordinary ore. These will absorb the heat which passes through the furnace walls and become highly heated prior to delivery to the 5 furnace.

The advantages of this construction of furnaces are, that a number of smelting units, each complete in itself, are built around a mixing chamber which is common to all, and the molten charges of the several furnaces may be tapped into the common mixing chamber, and a more uniform grade of metal output is thus obtainable, any little variation, intentional or unavoidable, of the ore used in the several furnaces 10 being merged in the total.

The furnace as a whole has also the advantage of economy in the construction of it, and in the association with the other furnaces and with the smelting chamber, there 15 is economy in the head used, the walls being contiguous and where possible jacketed with air or with ore, both of which are used in the furnaces.

By arranging the separate smelting furnaces as I have done around a central mixing chamber, and serving them with current on the three phase delta system, I am enabled to increase the gross output of the furnace without increasing the amount of current necessary to produce that output, and can use a current up to the limit of voltage it is safe to handle, say a thousand volts. 25

The carbon electrodes being connected on the three phase delta system with a suitable number of furnaces according to the voltage to be used in each phase of the connection, this number can be varied at will to suit the voltage which the nature of the charge may 30 require in each furnace, by cutting out or in one or two furnaces as required.

Thus in the drawing herewith four furnaces are shown in each phase of the circuit: While starting, one furnace of each group 35 may be practically cut out by lowering the carbon electrodes into contact with the charge, the short circuiting through which charge will proportionately increase the voltage in the three remaining furnaces. As soon as the charges in these three furnaces are raised to incandescence and less voltage 40 is required, the carbons of the short circuiting furnace are withdrawn from contact with the charge to their proper arcing position during the residue of the heat. 45

Having now particularly described my invention, I hereby declare that what I claim as new and desire to be protected in by Letters Patent, is:

60 1. An electrical iron smelting furnace, comprising a series of electrical smelting chambers disposed around a central mixing chamber, means for delivering ore separately to each smelting chamber, means for tapping the molten metal from each smelt- 65

ing chamber and for delivering it into the central mixing chamber, and means for tapping the central mixing chamber.

2. An electrical iron smelting furnace, comprising a series of electrical smelting 70 chambers disposed around a central mixing chamber with an ore heating chamber between each pair of smelting chambers, means for delivering ore separately to each smelting chamber, means for tapping the molten 75 metal separately from the several smelting chambers and for delivering it into a central mixing chamber, and means for tapping the central mixing chamber.

3. An electrical iron smelting furnace, comprising a series of electrical smelting 80 chambers disposed around a central mixing chamber, each smelting chamber having an air jacket space in its roof with means for delivering air into this roof air space and 85 for conveying it therefrom and delivering it into the smelting chamber, means for delivering ore to the several smelting chambers, means for tapping the molten metal from each smelting chamber and delivering 90 it into the central mixing chamber, and means for tapping the mixing chamber.

4. An electrical iron smelting furnace, comprising a series of electrical smelting 95 chambers disposed around a central mixing chamber, a conical ore hopper surmounting the mixing chamber, means for delivering the ore from the hopper into the several smelting chambers, means for delivering heated air into each smelting chamber and 100 for delivering the products of combustion from each chamber through the ore delivery chute, means for tapping the several smelting chambers and for delivering the molten metal into the central mixing chamber, and 105 means for tapping the mixing chamber.

5. An electrical iron smelting furnace, comprising a series of electrical smelting 110 chambers disposed around a central mixing chamber, means for delivering ore separately to each smelting chamber, means for connecting the carbon electrodes of the several smelting chambers to a common source of electrical energy on the three phase delta system, means for tapping the molten metal 115 separately from the several smelting chambers, and for delivering it to the mixing chamber, and means for tapping the mixing chamber.

6. An electrical iron smelting furnace, 120 comprising a series of electrical smelting chambers disposed around a central mixing chamber, the lateral walls of said smelting chambers being parallel to their radial middle lines, an ore heating chamber occupying 125 the space between the lateral walls of adjacent smelting chambers, a conical ore hopper supported over the central mixing chamber, means for delivering ore from the ore hopper to the inner side of each smelting 130

chamber adjacent the level of the electrode ends, each smelting chamber having an air space in its roof to the inner end of which external air is delivered and from the outer end of which the heated air is delivered to the furnace chamber, means for delivering the products of combustion in each furnace

chamber through its ore delivery, means for tapping each furnace chamber and for delivering the molten metal therefrom into 10 the central mixing chamber, and means for tapping the central mixing chamber.

In testimony whereof I affix my signature.
JAMES D. SHIPTON.
